ESCAPEMENT

Fritz Eibert, Munich, Germany, assignor to Robert Wolff, Basel, Switzerland

Application November 20, 1934, Serial No. 753,796
In Germany April 3, 1934

5 Claims. (Cl. 197—88)

The present invention relates to an improved escapement and more particularly to a paper carriage escapement for typewriters.

In order to speed up the step by step displacement of the paper carriage in typewriters and at the same time to utilize the force exercised by the carriage spring on the escapement for speeding up the return movement of the depressed key lever, it has been already proposed to provide the displacement pawl with a wedge like surface engaged by the teeth of the ratchet wheel or rack under the influence of the carriage spring. As a modification of the same principle it has been also suggested to provide the ratchet wheel with teeth having an oblique or wedge like surface which were engaged by a displacement pawl of conventional design. Although these arrangements have been successful in speeding up the operation of the paper carriage and of the key levers all escapements of this type had the common disadvantage that frequently the paper carriage would be displaced by several steps if the operator was too slow in withdrawing his finger from the depressed key. Of course, this circumstance interfered seriously with the correct operation of the typewriter confronting the art with a problem for which as far as I am aware of no satisfactory solution has been offered.

I have discovered that it is possible to eliminate all of the aforesaid shortcomings of the prior escapements and to provide a completely satisfactory and reliable escapement device in a remarkably simple manner.

It is an object of the present invention to provide an improved paper carriage escapement for typewriters which permits quick and easy displacement of the paper carriage and utilizes part of the energy stored in the carriage spring for the return movement of the key lever, type lever, and the like.

It is another object of the present invention to provide an escapement device for typewriters which embodies the advantages of wedge-like surfaces in its co-operating parts and at the same time eliminates the danger of unintended movements of the paper carriage when the depressed key lever is released too slowly.

A further object of the invention is to incorporate a safety catch into one of the co-operating members of the escapement and thereby insure easy and reliable displacement of the paper carriage at all speeds or conditions of operation.

The invention also contemplates an improved ratchet which is provided with wedge shaped

teeth having a safety catch which can be easily manufactured and which can be used for converting escapements of conventional design into my improved escapement.

Other objects and advantages of my invention will become apparent from the following description taken in conjunction with the accompanying drawings, in which:

Fig. 1 shows an embodiment of my invention including a vertical section of the key action and illustrated the displacement pawl in its normal or rest position;

Fig. 2 is a fragmentary view of the pawls and ratchet shown in Fig. 1 illustrating the displacement pawl in its position when the type lever is depressed;

Fig. 3 is a similar view depicting the displacement pawl partly returned by the ratchet tooth under the influence of the carriage spring said pawl being locked by the safety catch due to the key not being released yet;

Fig. 4 shows the displacement pawl in the last part of its return movement;

Fig. 5 is a fragmentary view of a modified embodiment of the invention depicting the position of the displacement pawl when the type lever is depressed;

Fig. 6 is a similar view illustrating the displacement pawl when the type lever has been partly returned but the key is not released yet;

Fig. 7 shows the displacement pawl in its position of rest;

Fig. 8 shows another modified embodiment of the invention;

Fig. 9 is a fragmentary view of the pawls and ratchet shown in Fig. 8 depicting the displacement pawl in its position of rest;

Fig. 10 is a similar view illustrating the pawls when one of the key levers is depressed;

Fig. 11 shows the displacement pawl partly returned and engaged by the safety catch on the ratchet wheel tooth;

Fig. 12 is a somewhat fragmentary plan view of my improved ratchet wheel with safety catch;

Fig. 13 shows the assembly of my improved ratchet wheel;

Fig. 14 is a front elevational view, somewhat fragmentary, of my improved ratchet wheel having a safety catch in co-operation with a conventional displacement pawl; and

Figs. 15 and 16 show diagrammatically two consecutive steps in the operation of the escapement illustrated in Fig. 14.

According to the principles of the present invention, a novel combination is provided involv-

- ing a ratchet and an escapement pawl either of which is provided with a wedge-like surface and a safety catch. The safety catch preferably has a short angular surface which is preferably normal or perpendicular to the direction in which the teeth of the ratchet wheel are moving. This angular surface will act as a safety catch and will detain the ratchet wheel teeth momentarily during its sliding off movement, if the depressed key is not released fast enough. In some cases, I prefer to provide the displacement pawl or the pawl carrier with a very light spring in order to return the pawl or carrier to its normal position of rest.
- 15 The principle of my invention can be also employed in escapements of the type where the wedge-like surface is on the teeth of the ratchet wheel. In this case I add the angle surface or safety catch to the teeth of the ratchet wheel, which I provide with a short extension surface preferably at right angles or normal to the direction of movement of the ratchet wheel. The practical results will be the same as when the safety catch is applied to the displacement pawl.
- 20 I found that the latter modification is especially adaptable to be used as an attachment or replacement part for typewriters of conventional design, because the conventional ratchet wheel can be easily exchanged and replaced with my improved ratchet wheel provided with wedge-like teeth and safety catch thereby improving the performance of the typewriter quite considerably. Of course, an old pawl in a conventional typewriter can be replaced just as easily with a new pawl having a wedge-like surface and a safety catch as the replacement of the old ratchet wheel.
- Referring more particularly to Figs. 1 to 4, ratchet wheel *k* is rotatably arranged between two bearings *l* and *m* and is provided with teeth *d*. The ratchet wheel co-operates with a displacement pawl *b* integral with a pawl carrier *t* pivoted at *i* and held in its normal position by spring *h*. On the right side of pawl carrier *t*, a retaining pawl *p* is mounted on a pivot *r* and held in its normal or rest position by spring *s*. The displacement pawl *b* has a wedge-like surface *c* which is provided at the end thereof with a safety catch *f*. This safety catch is preferably arranged at right angles to the direction of movement of the ratchet wheel, as may be clearly seen from Fig. 1.
- The left side of Fig. 1 shows a conventional key action comprising key lever *K* connected by link *L* to front link *M* which in turn is connected by link *N* to the type lever *T*. Link *S* is connected at one end to member *O* rigidly fastened to link *N* and at its other end is hooked around the universal bar *u*. The type lever *T* is held in its normal position by means of spring *R* and strikes on platen *P* when actuated. The lower end of the pawl carrier *t* is provided with a resiliently mounted little roller *a* which is adjustable by means of screw *v* and is adapted to co-operate with the universal bar.
- 65 The operation of the aforesaid embodiment of my invention is apparent to those skilled in the art. When key lever *K* is depressed, through link *L*, front link *M* and link *N* the type lever *T* will be actuated and will strike against platen *P*. At the same time link *S* will pull the universal bar *u* to the left which in turn will engage roller *a* and actuate pawl carrier *t*. This will displace escapement pawl *b* so that its wedge shaped surface *c* will rest on or will engage the ratchet tooth *d* as may be seen in Fig. 2. At the same

time the retaining pawl *p* will release the ratchet wheel and consequently tooth *d* under the influence of the carriage spring will move in the direction of the arrow along and in contact with the wedge-like surface *c* of the displacement pawl *b*. This action will cause the displacement pawl *b* to move out of its path until the ratchet tooth *d* with its surface *e* abuts the safety catch *f* as depicted in Fig. 3. The pawl carrier *t* and the displacement pawl *b* under the influence of spring *h* will continue their return movement as soon as the depressed key is released and they will return to their normal position of rest. In this return movement, the pawl is assisted by having safety catch *f* sliding off surface *g* of the ratchet tooth.

Referring now to Figs. 5 to 7, they illustrate my improved wedge-like displacement pawl in co-operation with a ratchet wheel of conventional design having rectangular teeth *d*-2. In view of the similarity of construction, the description will not have to be repeated and similar reference characters are used to denote parts identical with those appearing in Figs. 1 to 4. The operation of this combination is similar to the one described hereinabove and will be readily understood from the drawings showing the escapement in successive phases of its operation. The only difference is that due to the rectangular shape of the ratchet teeth *d*-2 the displacement pawl will be returned to its normal position of rest immediately after the depressed key has been released.

It is to be observed that the escapement operates in the described manner only when the key is allowed to return slowly to its normal position of rest. When typing fast, the displacement pawl will be returned completely to its normal position of rest in one movement due to the first impulse exercised by the ratchet tooth on the wedge surface of the displacement pawl.

In the other embodiment of my invention illustrated in Figs. 8 to 13, a safety catch is incorporated in each wedge-like tooth of the ratchet wheel which co-operates with pawls of conventional design. Similar reference characters are used in Figs. 8 to 13 to designate parts identical with those described hereinabove and illustrated in Figs. 1 to 7. Ratchet wheel *k*-1 is provided with wedge-like teeth *d*-1 having a surface *g*-1. At or near the end of each tooth, a catch *f*-1 is incorporated which is preferably at right angles to the direction of rotation of the ratchet wheel. Displacement pawl *b*-1 and pawl carrier *t*-1 which are integral, are pivoted at *i*-1 and the displacement pawl is capable of engaging the teeth of the ratchet wheel and particularly safety catch *f*-1. The retaining pawl *p*-1 is pivotally arranged in the conventional manner on pawl carrier *t*-1.

Figs. 8 and 9 show the pawls in the normal position of rest. When a key is depressed link *S*-1 will displace the universal bar *u*-1 to the left so that this will strike against screw *v*-1 and will actuate the pawl carrier *t*-1. The end of the displacement pawl *b*-1 will rest on or will be in contact with the wedge shaped surface *g*-1 of tooth *d*-1 as may be seen in Fig. 10. At the same time the retaining pawl *p*-1 will release the ratchet wheel so that tooth *d*-1 under the influence of the carriage spring communicated through the rack *x* and gear *y* will move in the direction of the arrow. This will move pawl *b*-1 in the direction of its normal or rest position until it engages or abuts the

safety catch *f*—1 as may be seen in Fig. 11. In this manner, the escapement will be locked in this position momentarily and unintended displacements of the carriage will be impossible before the key is completely released.

I have found that when manufacturing ratchet wheels embodying the principles of my invention, it is the simplest to make them from two pieces which are subsequently rigidly connected to each other. An improved ratchet wheel made with this method may be seen in Figs. 12 and 13. Part *o* of the ratchet wheel carries the wedge-like teeth and part *n* the safety catches. After these parts have been made up separately 15 and brought in the correct position in relation to each other, they are rigidly united by means of screws, rivets or the like.

My improved escapement permits the insertion of a resilient member between the universal bar 20 and the pawl carrier of any typewriter. Of course, the resilient member will have a suitable construction so as to displace the pawl carrier from its position of rest when one of the keys is depressed. This construction produces 25 an easy and elastic touch and has a tendency to speed up the return movement of the type lever. In addition, the escapement operation proper will be much quicker and smoother because the carriage spring will exercise greater force on the 30 wedge surface than the associated resilient member or buffer spring.

Fig. 14 shows my improved ratchet wheel embodying a wedge-like surface and safety catch in co-operation with a conventional escapement similar to that of the well-known Royal typewriter. Fig. 14 closely resembles the escapement illustrated in Fig. 8, the displacement pawl *b*—2 being provided with a small ball *w* rotatably mounted at the end of the displacement pawl. Similar reference characters have been used both 40 in Fig. 8 and Fig. 14 to denote identical parts. It is believed that the construction and operation of this particular embodiment of my invention will be readily understood by those skilled 45 in the art from the foregoing description given in connection with Figs. 8 to 11.

Figs. 15 and 16 are fragmentary and diagrammatical views of two successive phases in the operation of this escapement. Fig. 15 depicts the position of the retaining pawl and of the 50 displacement pawl in relation to the tooth of the ratchet wheel when the key lever is actuated, while Fig. 16 shows the pawls in their locked position when the key lever has not been completely released yet.

55 I claim:

1. An escapement device for typewriters comprising a ratchet wheel having a plurality of teeth provided with bevel surfaces, a detaining pawl adapted to engage a tooth of said ratchet wheel in its normal position of rest and to release same when actuated, a displacement pawl slidably receiving said disengaged tooth, means for actuating said pawls during the forward 60 stroke of a type lever, and a short safety catch surface for each tooth of the ratchet wheel adjoining the said bevel surface substantially at right angles to the path of said tooth and adapt-

ed to co-operate with the sliding off displacement wall to retain and lock the ratchet wheel until the complete release of the depressed key.

2. An escapement device for typewriters comprising a ratchet wheel having a plurality of teeth bearing bevel surfaces, a detaining pawl adapted to engage a tooth of said ratchet wheel in its normal position of rest and to release same when actuated, a displacement pawl capable of slidably receiving said disengaged tooth, means for actuating said pawls during the forward stroke of a type lever, and a short safety catch surface for each tooth of the ratchet wheel adjoining the said bevel surface towards the displacement pawl substantially at right angles to the path of said tooth, said safety catch surface being adapted to engage the sliding off displacement pawl and to detain and to lock said ratchet wheel until the complete release of the depressed key.

3. An escapement device for typewriters having keys comprising a ratchet wheel having a plurality of teeth bearing angular surfaces, a pawl carrier adapted to receive impulses from the forward stroke on the keys of said typewriter, a detaining pawl mounted on said carrier and adapted to engage a tooth of said ratchet wheel in the normal position of rest of the pawl carrier and to release same when said pawl carrier is actuated, a displacement pawl on said carrier 30 adapted to slidably receive said disengaged tooth, resilient means for maintaining said carrier and said pawls in their initial position, and a short safety catch surface for each tooth of the ratchet wheel adjoining the said angular surface towards the displacement pawl substantially at right angles to the path of said tooth, said safety catch surface being adapted to engage the sliding off displacement pawl and to detain and to lock said ratchet wheel until said carrier and said key are 40 completely released.

4. In a ratchet wheel for typewriter escapements, the improvement which comprises a circular member having a plurality of teeth each bearing an angular surface, a second circular 45 member having identical number of teeth at right angles to the plane of said members and adapted to form extensions for said angular teeth, and means for rigidly connecting said circular members to each other.

5. An escapement device for typewriters comprising a powered ratchet wheel having teeth, detaining and displacement pawls adapted to engage one of said teeth at a time and having surfaces co-operating with corresponding surfaces 55 on said ratchet wheel teeth, at least one of said co-operating surfaces being at an angle other than right angle to the direction of movement of said ratchet wheel, means for actuating said pawls during the forward stroke of a type lever 60 to permit movement of said ratchet wheel by one tooth, and a safety catch surface adjoining said angle surface and at substantially right angles to the direction of movement of said ratchet wheel capable of locking the other co-operating 65 surface after the forward stroke of the type lever until the complete release of the depressed key.

FRITZ EIBERT.
